(57) **CLAIM**

The ornamental design for a fitting for plasma ARC torch, as shown and described.

DESCRIPTION

FIG. 1 is a perspective view of a cutting torch fitting showing my new design;

FIG. 2 is a front elevation view thereof;

FIG. 3 is a top plan view thereof;

FIG. 4 is a right end elevation view thereof; and,

FIG. 5 is a left end elevation view thereof.

The rear elevation view is identical to the front elevation view, and the bottom plan view is identical to the top plan view.
